US0D1020737S

(12) **United States Design Patent** (10) **Patent No.:** **US D1,020,737 S**
(45) **Date of Patent:** **** Apr. 2, 2024**

(54) **ELECTRONIC DEVICE**

(71) Applicant: **Samsung Electronics Co., Ltd.**, Suwon-si (KR)

(72) Inventor: **Wonkyung Jang**, Suwon-si (KR)

(73) Assignee: **Samsung Electronics Co., Ltd.**, Suwon-si (KR)

(**) Term: **15 Years**

(21) Appl. No.: **29/783,683**

(22) Filed: **May 14, 2021**

(30) **Foreign Application Priority Data**

Nov. 17, 2020 (KR) 30-2020-0055574

CLAIM

I claim the ornamental design for an electronic device, as shown and described.

DESCRIPTION

FIG. 1 is a front perspective view of an electronic device showing my new design;

FIG. 2 is a front view thereof;

FIG. 3 is a rear view thereof;

FIG. 4 is a left-side view thereof;

FIG. 5 is a right-side view thereof;

FIG. 6 is a top view thereof;

FIG. 7 is a bottom view thereof; and,

FIG. 8 is a rear perspective view thereof.

The broken lines in the figures depict portions of the electronic device that form no part of the claimed design.

1 Claim, 6 Drawing Sheets
